Patented July 6, 1920.

FIG. 3

FIG. 2

FIG. 1

INVENTORS:

WILLIAM F. MINOR

PHIL C. KELLER

THOMAS W. ROLPH

BY *Albert G. Davis*
THEIR ATTORNEY

UNITED STATES PATENT OFFICE.

WILLIAM F. MINOR AND PHIL C. KELLER, OF CLEVELAND, AND THOMAS W. ROLPH,
OF SEBRING, OHIO, ASSIGNORS TO GENERAL ELECTRIC COMPANY, A CORPORATION
OF NEW YORK.

REFLECTOR.

1,345,796.

Specification of Letters Patent.

Patented July 6, 1920.

Application filed March 15, 1919. Serial No. 282,868.

To all whom it may concern:

Be it known that we, WILLIAM F. MINOR and PHIL C. KELLER, citizens of the United States, residing at Cleveland, county of 5 Cuyahoga, State of Ohio, and THOMAS W. ROLPH, a citizen of the United States, residing at Sebring, county of Mahoning, State of Ohio, have invented certain new and useful Improvements in Reflectors, of which 10 the following is a specification.

Our invention relates to reflecting equipment for light sources and more particularly to combinations of glass and metal used for reflecting equipment.

15 Metal reflectors are used extensively in industrial lighting because of their unbreakability as well as because they shield the bright concentrated light sources usually installed in manufactures and such places. 20 Such reflectors usually direct all of the light into the lower hemisphere and leave the ceiling dark or illuminated only by light reflected back from the lower hemisphere, which is ordinarily dark colored and 25 of a non-reflecting character. The unilluminated ceiling is in sharp contrast with the brightly lighted working plane and this contrast produces eye fatigue in those workmen who may have occasion to look up from their work. Besides the physiological effect there is an adverse psychological effect, caused by the unpleasant vault-like appearance of the shop, which is undesirable from 30 the standpoint of the employee. Furthermore, shafting or machinery mounted upon the ceiling is hard to watch if not illuminated to some extent. An additional disadvantage of the metal reflector is that with 35 the unlighted ceiling, shadows are sharper 40 because the light comes directly from a bright source. While whole glass reflectors would light up the ceiling, they are seldom used in industrial plants because of breakage and glare.

45 Our invention is a novel combination of glass and metal reflector, so constructed that light is transmitted to the ceiling while glare from the source is prevented and danger of breakage minimized. We accomplish 50 this result by replacing a part or all of the upper metal portion of the usual metal reflector with glass which may be transparent but is preferably translucent so as to conceal the inclosed parts and to minimize

glare. Moreover, the use of the proper density of translucent or diffusing glass will give any desired relation between reflected and transmitted light. 55

In the accompanying drawing, Figure 1 is an elevation partially in section of a reflector embodying our invention, and Figs. 2 and 3 are elevations partially in section of modifications thereof.

Referring to Fig. 1, it will be seen that the upper portion of the ordinary metal reflector has been replaced by a glass reflecting and transmitting element 1. The element 1 is preferably carried by three metal straps 2 each attached at its lower end as by welding to the reflector metal element 3, and at its upper end to a ring 4. These straps are preferably twisted in the middle to prevent shadow on the element 1. The ring 4 is inserted in the heel 5, being attached thereto by means such as screws 6. The shoulder 7 on the lower part of the heel prevents warping of the heel during the enameling process and furnishes a seat for the upper edge of the glass element 1 as well as preventing the glass from dropping out should the reflector be inverted. The flange 8 on the upper end of the reflector metal element 3 is preferably provided as it serves to prevent distortion of the upper end of the skirt, during the enameling process 85 and also improves the appearance to a certain extent.

In the modification shown in Fig. 2 only a part of what is ordinarily the upper metal portion is replaced by glass. The straps 2 are provided as in the other case and each is attached to the heel and to the lower or metal element of the reflector as before. In 90 this case, however, the glass rests upon the lower metal part of the reflector. The flange 9 adds strength to the upper edge of the metal element of the reflector and prevents direct light from being emitted between the lower end of the glass element and the metal element of the reflector. 100

In the modification shown in Fig. 3, the metal reflector and heel are combined with a holder 10. The glass element 11 serves as a cover and extends down to the top of the metal element 3. In this case, the heel 12 is supported preferably by the spring fingers 13 of the holder 10. The glass element 11 is preferably resiliently supported at its up-

per edge in a spring clamp consisting of a pair of disks 14 forming a recess to receive the said glass element. The disks 14 are slipped over the threaded extension 15 of the holder 10 and compressed by the nut 16. The extension 15 is also threaded internally for the reception of a conduit or other support.

What we claim as new and desire to secure by Letters Patent of the United States, is,—

1. A reflector for use with artificial light sources comprising a lower metal light reflecting element, a metal heel spaced from said element, means connecting said reflecting element and said heel whereby the former is supported through the latter, and a glass transmitting element covering the space between said metal element and said heel.

2. A reflector for use with artificial light sources comprising a metal heel adapted to be received by a suitable supporting means, a lower metal light reflecting element spaced from and supported by said heel and a glass light transmitting element covering the space between the said heel and metal element and carried by them.

3. A reflector comprising a metal heel adapted to be received by suitable supporting means, a metal light reflecting element disposed below said heel and spaced there-

from, a light transmitting element covering the space between the said heel and said reflecting element and means extending from said heel to said reflecting element and disposed below said light transmitting element whereby said reflecting element is supported through said heel.

4. A reflector comprising a metal heel adapted to be received by suitable supporting means, a metal light reflecting element disposed below said heel and spaced therefrom, a light transmitting element covering the space between the said heel and said reflecting element and straps extending from said reflecting element to said heel and disposed below said light transmitting element whereby said reflecting element is supported through said heel.

5. A reflector comprising a metal heel, a metal reflecting element disposed below and spaced from said heel, a light transmitting element covering the space between said heel and said reflecting element and means whereby said reflecting element is supported through said heel and independently of said light transmitting element.

In witness whereof, we have hereunto set our hands this twelfth day of March, 1919.

WILLIAM F. MINOR.
PHIL C. KELLER.
THOMAS W. ROLPH.
